FOUR-SIDED SAFETY RAZOR AND BLADE

Maurice Falk, New York, N. Y.

Application July 10, 1935, Serial No. 30,591

2 Claims. (Cl. 30—72)

This invention relates to new and useful improvements in a four sided safety razor and blade.

The invention has for an object the construction of an article as mentioned which is characterized by a four sided head piece with a central threaded stud and several spaced pegs, a four sided razor beneath said head piece, a four sided guard beneath the razor, and a handle threadedly engaging said stud to hold the head piece, blade and guard together.

More particularly, the invention has specific reference to a novel arrangement of the pegs and complementary receiving openings in the razor blade.

Still further the invention contemplates arranging the pegs in a straight line with the central threaded stud, and arranging the openings in the razor in the form of a cross so that the razor may be engaged on said stud and pegs in several adjusted positions.

Still further the invention proposes a construction whereby each of the edges of the four sided blade is supported upon the head piece and guard in a reinforced condition.

Furthermore, the invention has for an object the association with the head piece of a means for holding any one of the sides in reinforced position to enhance the efficiency of the blade during shaving.

Another object of the invention is the construction of a device as described which is simple and durable and which may be manufactured and sold at a reasonable cost.

For further comprehension of the invention, and of the objects and advantages thereof, reference will be had to the following description and accompanying drawing and to the appended claims in which the various novel features of the invention are more particularly set forth.

In the accompanying drawing forming a material part of this disclosure:—

Fig. 1 is a plan view of an article constructed according to this invention.

Fig. 2 is a fragmentary sectional view taken on the line 2—2 of Fig. 1.

Fig. 3 is a perspective view of the blade per se.

Fig. 4 is a plan view of a guard per se of a razor according to another embodiment of the invention.

Fig. 5 is a perspective view of a modified form of blade to be used with the razor partially shown in Fig. 4.

Fig. 6 is an edge elevational view of Fig. 5.

Fig. 7 is a fragmentary vertical sectional view of the complete razor, this view being taken on

a section line which would pass through the line 1—1 of Fig. 4.

Fig. 8 is a view similar to Fig. 7 illustrating another modification.

Fig. 9 is a plan view of the razor shown in Fig. 8.

The four sided safety razor, according to this invention, comprises a four sided head piece 10 with a central threaded stud 11 and several pegs 12. A four sided razor blade 13 is arranged beneath the head piece and has an opening 14 through which the stud and pegs may pass. A four sided guard 15 is arranged beneath the razor blade and has openings 16 and 17 through which the pegs and the stud pass. A handle 18 is threadedly engaged on the central threaded stud 11 and tightly screwed therein for holding the head piece, the blade and the guard together in a unit.

The head piece 10 and the guard 15 are formed in curved quadrants which are adapted to curve the blade into four sections radiating from the center thereof so that each of the edges of the blade is reinforced. In Fig. 2 it should be noted that both the guard and the head piece are curved. This represents the curvature of two of the quadrants diametrically opposite each other. From Fig. 1, the quadrants may be noticed between the diagonally crossed lines indicated by the reference numerals 20. The blade 13 has cutout corners 13^a so that each of the edges thereof are free and may flex independently. The opening 14 is substantially in the form of two diagonally crossed arms 14^a and 14^b. At the junction of these arms there is sufficient space for the threaded stud 11 to pass. The pegs 12 may pass through either of the ends of the arms 14^a and 14^b. This permits the blade 13 to be set into position upon the razor in several different ways. It may be set with one face adjacent the head piece or the other face adjacent the head piece.

In addition, it may be turned to several different positions.

In Figs. 4—7 inclusive a modified form of the article is disclosed which distinguishes from the prior form in several details. More particularly, the pegs 12 and the central threaded stud 11 are arranged on a straight line which is parallel to certain of the sides of the razor. In addition, this form discloses a blade 13' which has an opening 14' consisting of branches 14^{aa} and 14^{bb} parallel to the sides of the razor. The diagonals of the blade are formed with narrow slots 22 so as to reduce the amount of metal at these

areas to render the blade more flexible. This is of value in that it then may be readily placed into the position controlled by the curvatures of the head piece and the guard.

5 In other respects this form of the invention is identical to the previous form and similar parts may be recognized by the same reference numerals.

In Figs. 8 and 9 a still further modified form 10 of the invention is disclosed in which provision is made for forcing one or more of the edges of the razor ends into curved shape to stiffen the razor as desired. More particularly, in this form there is a flat head piece 10' which has the stud 15 11 projecting from its center. This flat head piece cooperates with the curved guard 15. The guard 15 is curved in quadrants as indicated by the oblique lines 20 in Fig. 9. The blade 12, when placed in the razor, normally would have 20 all of its edges free since the parts may only be clamped tight at the center. Then, any one of the four sides of the razor may be placed into operative condition by screwing down the threaded elements 25 threadedly engaged through the head piece. These threaded elements are arranged in pairs for each of the quadrants. As shown in Fig. 8, the left hand side of the razor blade is forced into the curved position and is thus ready for use. The other sides of the razor 30 blade are free. The purpose of the arrangement is to only flex that edge of the blade which is to be used so as to stiffen it and make it perform efficiently, while the other edges are free to prevent undue stresses being placed upon the blade 35 which will interfere with the proper flexing of the edge which is used. It should be understood that if the blade is tightly held on the four sides it will not be as flexible if it is held tightly upon one side.

40 While I have illustrated and described the preferred embodiment of my invention, it is to be

understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. A four sided safety razor and blade, comprising a four sided head piece with a central 10 threaded stud and several pegs, a four sided razor blade beneath said head piece and having openings through which said stud or pegs pass, a four sided guard beneath said razor blade and having openings into which said stud and pegs 15 pass, and a handle threadedly engaging said stud and holding said head piece, blade and guard together, said head piece being flat, said guard being convexed, and means on the head piece and engageable against the sides of the blade selectively to conform any of the sides of the blade to the shape of the guard.

2. A four sided safety razor and blade, comprising a four sided head piece with a central 25 threaded stud and several pegs, a four sided razor blade beneath said head piece and having openings through which said stud or pegs pass, a four sided guard beneath said razor blade and having openings into which said stud and pegs pass, and a handle threadedly engaging said stud and holding said head piece, blade and guard together, said head piece being flat, said guard being convexed, and means on the head piece and engageable against the sides of the blade 30 selectively to conform any of the sides of the blade to the shape of the guard, comprising elements 35 threadedly engaging through said head piece and engaging the top portion of said blade for shaping the said blade.

MAURICE FALK. 40
